ELECTRICAL LEAD CONNECTOR

Hans Bader, Orland Park, Ill.

Application October 7, 1953, Serial No. 384,751

9 Claims. (Cl. 339—59)

This invention relates to lead connectors for electrical apparatus, and more particularly to such devices which afford separable connections for the lead wires of electrical equipment having relatively high values of operating current.

One of the general objects of my invention is to provide a lead connector embodying parts for making connections in a plurality of leads, and having separable housing elements which carry and normally enclose said parts.

As another object, the invention has within its purview the provision of a lead connector having terminal elements for making connections in a plurality of leads, and in which device means is provided for simultaneously applying contact pressure to the terminal elements.

My invention has for another object the provision of a lead connector unit having separable parts which each carry a plurality of lead connecting elements; said separable parts, during use, being normally clamped together, and having latch devices thereon which are adapted to ready engagement and disengagement to facilitate the assembly and disconnection of the parts.

It is another object of this invention to provide a lead connector for making separable connections in a plurality of lead wires having relatively high current carrying capacity, and wherein separable terminal elements for the lead wires are disposed in parallel relationship with insulating blocks interposed between the terminal elements for adjacent leads, said terminal elements and insulating blocks being laterally aligned and having means coacting therewith for applying pressure to maintain contact between the terminal elements without the use of clamping screws or bolts for each pair of connected terminal elements.

My invention further comprehends the provision of a lead connector suited to use on traction motors and the like and which incorporates a housing composed of two separable parts, each of which parts carries the terminals for one of the sets of leads to be connected therethrough, one of the parts being adapted to relatively permanent mounting with respect to a structure, and the other being constructed and arranged for releasable attachment to said one of the parts by a clamping structure which, in addition to securing the parts together, also clamps the connected terminals in their contacting relationship.

In this invention, I have for another object the provision of a lead connector for making separable connections in a plurality of lead wires, and wherein a latching device which serves to interconnect the separable parts during the processes of assembly and disassembly of the separable parts of the connector also serves as a locator for effecting proper alignment and placement of the parts while they are being secured in place. This latching device, in the disclosed structure, also serves to relieve the contacting terminals of the connector from strains during use.

As a further object, my invention comprehends the provision of a lead connector wherein readily releasable latching devices hold the parts in their assembled relationship while retaining pressure is either applied to or

2

relieved from the terminal elements of the parts, and wherein the latching devices also serve to lock the pressure applying parts during use.

Other objects and advantages of the invention will be apparent from the following description and the accompanying drawings in which similar characters of reference indicate similar parts throughout the several views.

Referring to the four sheets of drawings:

Fig. 1 is a side elevational and somewhat diagrammatic view depicting a typical manner of use and arrangement for the application of a preferred embodiment of my lead connector to the power leads of a traction motor of the type utilized on locomotives, street cars and the like;

Fig. 2 is an end sectional view drawn to a larger scale than Fig. 1 and wherein the structure of my lead connector is viewed substantially as indicated by a line 2—2 in Fig. 1 and the accompanying arrows;

Fig. 3 is a bottom plan view of the lead connector shown in Fig. 1, wherein the power leads are indicated fragmentarily;

Fig. 4 is a side elevational view of the lead connector shown in Figs. 1, 2 and 3, drawn to a larger scale than Fig. 1, and wherein the power leads are fragmentarily illustrated;

Fig. 5 is an end sectional view of the lead connector, wherein the section is taken substantially as indicated by a line 5—5 of Fig. 4 and in the direction of the accompanying arrows;

Fig. 6 is a side sectional view wherein the section is taken substantially on a line 6—6 of Fig. 5 and in the direction of the arrows;

Fig. 7 is a top sectional view of the lead connector wherein the section is taken substantially on a line 7—7 of Fig. 6 and in the direction of the arrows;

Fig. 8 is an end elevational view of the lead connector with two separable parts thereof shown at positions displaced from one another and wherein a portion of one of the parts is broken away and shown in section, as viewed at the position of a line 8—8 of Fig. 6;

Fig. 9 is an exploded side elevational view which depicts three separable parts of my lead connector in separated relationships with respect to one another; and

Fig. 10 is a top plan view of one of the parts of my lead connector, substantially as viewed from the position of the line 10—10 of Fig. 9 and in the direction of the accompanying arrows.

In the accompanying drawings, I have illustrated an exemplary embodiment of my invention for illustrative purposes. Although not limited to use on traction motors, as may be readily understood, such adaptation, as depicted in Fig. 1, is representative of a typical installation for showing one use for my lead connector and its adaptation thereto. As depicted in Fig. 1, my lead connector 12 is secured to and supported by an underframe structure 13 of a locomotive or the like, and is there utilized to provide a separable connection between portions 14 and 15 of power leads by which both the field and armature currents are supplied to a traction motor

16. As somewhat diagrammatically shown, and as customary, the traction motor of a locomotive or the like is supported relative to a driven axle 17 on one of the locomotive trucks, and is connected to that axle for driving purposes through gears such as 18 and 19. It becomes necessary with relative frequency to disconnect traction motors and to remove them from a locomotive truck for repair or replacement. Thus, it is desirable to provide separable connections in the power leads for the motor which are not only adapted to ease of separation

and connection, but which are also suited to the maintenance of firm and low resistance connections during the regular use to which equipment of this type is subjected.

Having reference to the other views of the drawings,

as well as to Fig. 1, my disclosed lead connector 12 embodies two terminal and lead supporting parts 20 and 22 which together constitute a housing of hollow and substantially boxlike structure. The housing part 20, as illustrated, includes a top wall 23 and an end wall 24 disposed in substantially right-angular relationship to one another; these walls preferably being made integrally of a single sheet of metal having portions 25 and 26 angularly disposed with respect to one another and coated exteriorly on all surfaces with a relatively heavy covering 27 of insulating material, such as rubber. Insulating grommets 28 and 29, of a material such as rubber, are firmly and tightly fitted into openings in the end wall 24 to provide seals and supports for insulated power leads such as 14a, 14b, 14c and 14d. Although the grommets 28 and 29 in the illustrated structure each carry two of the lead wires, it may be understood that individual grommets for each lead, or other combinations of such grommets, may be utilized.

The other terminal and lead supporting part 22 of the illustrated structure includes a bottom wall 30, an end wall 32 in substantially right-angular relationship to the bottom wall 30 and disposed for mounting in opposed relationship to the end wall 24 of the terminal and lead supporting part 20, as well as opposed side walls 33 and 34, all of which walls are made from a formed piece of sheet metal covered internally and externally by layers of insulating material 35. The end wall 32 has openings therein, through which grommets 36, 37 and 38 of an insulating material, such as rubber, are tightly fitted to carry lead wires 15a, 15b, 15c and 15d in separated and insulated relationship, as shown in Fig. 3. Also, the side walls 33 and 34 have openings 39 and 40 therein, as shown in Fig. 5, which openings are substantially at the mid-portions of the respective side walls and are in opposed and substantially aligned relationship relative to one another.

The side walls 33 and 34 and the end wall 32 of the terminal and lead supporting part 22 are of substantially the same height relative to the bottom wall 30 of that part and, in the disclosed structure, they have inwardly extending flanges 42, 43 and 44 respectively thereon which are adapted to seat against the inner surface of the top wall 23 of the terminal and lead supporting part 20. Also, the top wall 23 of the terminal and lead supporting part 20 has marginal flanges 45, 46 and 47 thereon which overlie the outer margins of the side walls 33 and 34 and the end wall 32 respectively of the terminal and lead supporting part 22, when the two parts are in their assembled relationship. Furthermore, the bottom wall 30 of the terminal and lead supporting part 22 has a shoulder 48 thereon which engages the inner surface of the end wall 24, as well as an outwardly extending flange 49 extending from the shoulder 48 and disposed for mounting in overlapping relationship with respect to an outwardly extending flange 50 on the lower edge of the end wall 24 of the terminal and lead supporting part 20. Thus, the terminal and lead supporting parts of the disclosed structure have overlapping and angularly disposed surfaces along their adjoining edges which serve to provide a tightly sealed enclosure of boxlike structure when the parts are assembled together.

Metal strips 52 and 53 are secured to the outer edges of the top wall 23 of the terminal and lead supporting part 20 by removable fastening means, such as cap screws 54, threaded into lugs 55 and 56 secured to opposite end portions of that top wall structure. In use, the strips 52 and 53 are secured to a support, such as the under-frame structure 13, as by welding at 57 (Figs. 4 and 9) thereby to provide a relatively permanent support for the terminal and lead supporting part 20 on a structure, such as a locomotive. The other terminal and lead supporting part 22 is adapted to be removably supported relative to the terminal and lead supporting part 20 by a structure which will be more fully described.

Internally of the terminal and lead supporting part 20, terminal elements 58, 59, 60 and 62 are secured and electrically connected to the power leads 14a, 14b, 14c and 14d respectively. In the disclosed structure, the terminal elements 58, 59, 60 and 62 have substantially flat contacting surfaces 63, 64, 65 and 66 respectively and are mounted in spaced relationship with their contacting surfaces substantially parallel to one another. A block of insulating material 67 is mounted between adjacent surfaces of the terminal elements 58 and 59, which terminal elements have their contacting surfaces 63 and 64 facing outwardly with respect to the insulating block 67. In like manner, a block of insulating material 68 is mounted between adjacent surfaces of the terminal elements 60 and 62 and the contacting surfaces 65 and 66 of those terminal elements face outwardly with respect to the insulating block 68. Each of the insulating blocks 67 and 68 is removably held in place between its adjacent terminal elements by means such as a wire bracket 69. In the disclosed structure, each of the wire brackets 69 has a ringlike end portion 70 mounted on a stud 72 which is secured to the inner surface of the top wall 23 of the terminal and lead supporting part 20. Each such bracket also has a relatively straight portion 73 which extends through the mid-portion of one of the insulating blocks, through a spacing collar 74 at the end of the block remote from the stud 72 and into the mid-portion of one of the grommets 28 and 29.

Also in the disclosed structure, the mid-portions of opposite end surfaces of the insulating blocks 67 and 68 have slots 75 and 76 therein which extend across the insulating blocks in directions substantially parallel to the contacting surfaces of the adjacent terminal elements. Resilient clips 77 and 78, which are preferably made of wire coated with a highly effective insulating material, are engaged in slots 75 and 76 of each insulating block and have portions engaged in grooves 79 and 80 which extend along opposite side surfaces of the terminal elements adjacent the opposite faces of each insulating block. These clips serve to aid in holding the adjacent insulating blocks and terminal elements in aligned relationship laterally of the contacting surfaces of the terminal elements.

In the terminal and lead supporting part 22, terminal elements 82, 83, 84 and 85 are secured and electrically connected to lead wires 15a, 15b, 15c and 15d respectively and they have substantially flat contacting surfaces 86, 87, 88 and 89 disposed in spaced and substantially parallel relationship relative to one another. The terminal elements 82 and 85 are near the side walls 33 and 34 of the terminal and lead supporting part 22, while the terminal elements 83 and 84 are in spaced relationship at the mid-portion of that terminal and lead supporting part. The contacting surfaces of the respective terminal elements are also in substantial alignment in a direction lateral to those surfaces.

An insulating block 90 is mounted between the terminal elements 83 and 84 with its opposed side surfaces engaging the surfaces of the terminal elements which are opposite their contacting surfaces. As in the instance of the insulating blocks 67 and 68 which are utilized between terminal elements in the terminal and lead supporting part 20, the insulating block 90 is held in place by a wire bracket 69 having a ringlike end portion 70 secured to the bottom wall 30 of the terminal and lead supporting part 22 by a stud 72, as well as a substantially straight portion 73 which extends through the insulating block, through a spacing collar 74 and into the grommet 37. Also like the insulating blocks in the other terminal and lead supporting part, the insulating block 90 has slots 75 and 76 in the mid-portions of its opposite ends, which slots extend in substantially parallel relationship to the contacting surfaces of the terminal elements 83 and 84 and carry insulated and resilient wire clips 77 and 78 which have portions engaging grooves 79 and 80 in the opposite edges of the adjacent terminal elements 83 and 84.

At the opposite sides of the terminal and lead supporting part 22, pressure plates 92 and 93 are mounted for linear movement in the openings 39 and 40 respectively in the side walls 33 and 34. In the disclosed structure, ribs 94 and 95 are secured in spaced relationship to the outer surfaces of the pressure plates 92 and 93 respectively and project outwardly from those pressure plates, so that their end surfaces are exposed exteriorly of the opposite side walls of the terminal and lead supporting part 22. Insulating blocks 96 and 97 are mounted between the terminal elements 82 and 85 and the adjacent pressure plates 92 and 93 respectively, and are secured in place by projecting tabs 98 and 99 on the respective pressure plates and insulating spacers 100 and 102 interposed between the tabs and the opposite ends of the respective insulating blocks and preferably having portions extending into recesses in the opposite ends of the insulating blocks. Also, screws 103 and 104, desirably of the socket head type, extend through the pressure plate 92 and 93 respectively and have shoulders 105 and 106 engaging the exterior surfaces of the pressure plates. As in the instance of the other adjacent terminal elements and insulating blocks, resilient and insulated wire clips 77 and 78 extend through end slots 75 and 76 in the insulating blocks 96 and 97 and have portions engaging grooves 79 in opposite edges of the terminal elements 82 and 85.

In my disclosed structure, the contacting surfaces 64 and 65 of the terminal elements 59 and 60 in the terminal and lead supporting part 20 are spaced to receive therebetween and engage the contacting surfaces 87 and 88 of the terminal elements 83 and 84 in the terminal and lead supporting part 22 when those terminal and lead supporting parts are brought together in their assembled relationship to one another. Also, the contacting surfaces 63 and 66 of the terminal elements in the terminal and lead supporting part 20 are disposed and aligned for contacting engagement with the contacting surfaces 86 and 89 of the terminal elements 82 and 85 in the terminal and lead supporting part 22 when the terminal and lead supporting parts are brought together in their assembled relationship. When thus assembled, and as shown in Figs. 5 and 7, the engaged terminal elements and the intervening insulating blocks together provide an aligned series extending from one pressure plate to the other, whereby pressure applied to the outer edges of the ribs 94 and 95 on the pressure plates 92 and 93 serves to hold the adjacent contacting surfaces of all of the terminal elements firmly together, so as to maintain good electrical contact therebetween.

In my disclosed lead connector, I have provided a clamping structure which not only serves to hold the contacting terminal elements in firm engagement during use, but which also holds the terminal and lead supporting parts in their assembled relationship and embodies a releasable latch structure for holding the parts in their assembled relationship during the tightening or loosening of the pressure on the terminal elements for purposes of assembly and disassembly of the parts. Although the assembly and disassembly of the separable parts of my lead connector can be readily and quickly accomplished with my disclosed clamping structure, the necessity of manually holding the parts together while the contact pressure is applied or relieved is avoided.

In my disclosed clamping structure, an adjustable clamping element, such as a bolt 107 carrying a nut 108 is supported for rotation relative to the terminal and lead supporting part 22 by spaced ribs 109 and 110 secured to the outer surface of the bottom wall 30 of the terminal and lead supporting part 22 and adjacent substantially U-shaped parts 112 and 113 which are also secured to the outer surface of the bottom wall 30. At opposite ends of the bolt 107 and outside of the terminal and lead supporting part 22, levers 114 and 115 are mounted so that the levers extend laterally across the exteriors of the side walls 33 and 34 and across the mid-portions of the pres-

sure plates 92 and 93, with the bolt 107 extending through opposed end portions of the levers. In my preferred structure, the levers 114 and 115 are made of formed metal strip material and are hollow, with the edges of the strip material serving as the force transmitting portions thereof. At the mid-portions of the inner surfaces of the levers 114 and 115, fulcrum plates 116 and 117 are secured thereto for engagement with the exposed outer edges of the ribs 94 and 95 on the pressure plates. The ends of the levers opposite those through which the bolt 107 extends project somewhat beyond the adjacent edges of the side walls 33 and 34 of the terminal and lead supporting part 22 to serve as guides for the assembly of the separable parts of the lead connector by engagement with substantially U-shaped portions 118 and 119 of the metal strips 52 and 53. It may be noted that the substantially U-shaped portions 118 and 119 of the metal strips 52 and 53 on the terminal and lead supporting part 20 serve as fixed anchors for the ends of the levers 114 and 115 opposite the pressure applying bolt 107. Thus, with the ends of the levers 114 and 115 engaged in the U-shaped portions 118 and 119, the tightening of the nut 108 on the bolt 107 applies pressure to the engaged contacting surfaces of the terminal elements 25 through the pressure plates and the aligned terminal elements and insulating blocks.

In addition to utilizing the levers 114 and 115 for effecting alignment of the separable parts of the lead connector during assembly and for effecting the application of holding force against the contacting surfaces of the terminal elements, I also have leaf springs 120 and 122 mounted internally of the hollow levers 114 and 115 and extending longitudinally thereof; the leaf springs 120 and 122 being supported by the screws 103 and 104 between spacing collars 123 and 124 and clamping nuts 125 and 126 on the screws. Both leaf springs 120 and 122 extend longitudinally of the levers 114 and 115 on both sides of the screws 103 and 104. The ends of the springs adjacent the bolt 107 are curved outwardly away from the levers and so that those end surfaces are normally aligned for engagement with the flat sides of the bolt head and nut to serve as locks to prevent the bolt and nut from turning; the locking actions of the springs being released by inward pressure of the springs longitudinally of the bolt, so that those springs are held out of alignment with the bolt head or nut, or both. The other ends of the springs 120 and 122 are bent inwardly of the levers 114 and 115 and have latch elements 127 and 128 secured thereto with latching shoulder surfaces 129 and 130 normally projecting beyond the outer lever surfaces for engagement with holding surfaces 132 and 133 in recesses 134 and 135 respectively, which recesses are provided on the inner surfaces of the substantially U-shaped portions 118 and 119 of the strips 52 and 53. With this arrangement of parts, the engagement of the 55 latching surfaces holds the separable terminal and lead supporting parts of the lead connector in assembled relationship during either tightening or loosening of the pressure on the terminal elements by turning either the bolt 107 or the nut 108. Release of the latches is effected by the application of manual force against the end portions of the springs from the outsides of the levers and toward the terminal and lead supporting parts.

From the foregoing description and reference to the accompanying drawings, it may be readily understood that I have provided a lead connector embodying separable unitary parts, which parts not only co-operate to afford a tight closure for the terminal elements, but which are subject to ready assembly and disassembly with latches for holding the parts together in aligned relationship during the tightening and loosening of a clamp structure which holds the contacting surfaces of the terminal elements tightly together during use.

While I have illustrated a preferred embodiment of my invention, many modifications may be made without

departing from the spirit of the invention, and I do not wish to be limited to the precise details of construction, but desire to avail myself of all changes within the scope of the appended claims.

Having thus described my invention, what I claim as new and desire to secure by Letters Patent of the United States is:

1. A lead connector for electrical apparatus comprising two housing parts which fit together to provide a hollow box-type enclosure, said housing parts each having base and end walls adjoined together at adjacent ends and extending in angular relationship to one another from the adjoined ends, said base and end walls of each part also having end portions opposite the adjoined ends which interfit respectively with end portions of the end and base walls of the other part in the assembly of the parts, said base walls and said end walls of the two parts respectively being in spaced and opposed relationship to one another when the parts are assembled, the end walls of the parts each having an opening therein for the passage of lead wires therethrough, terminal elements mounted in spaced and substantially parallel relationship to one another in each of the housing parts in the angle formed between the base and end walls, said terminal elements each having substantially parallel flat faces on opposite sides thereof disposed in substantially normal relationship to the base and end walls of the part in which they are mounted, insulating blocks interposed between the flat faces of alternate pairs of adjacent terminal elements in the housing parts and at the outer flat faces of the terminal elements in one housing part, said terminal elements and insulating blocks being in staggered relationship relative to one another in the two housing parts to provide a series of contacting terminal elements and insulating blocks when the housing parts are assembled in aligned relationship to one another in a direction transverse to the flat faces, and clamping means on the housing parts for applying pressure to said series of contacting terminal elements and insulating blocks when the housing parts are fitted together.

2. A lead connector for electrical apparatus as defined in claim 1, and further characterized by engageable latch elements on the two housing parts including arms extending laterally of the mid-portions of opposite edges of the base walls at positions spaced from the end walls for holding the parts together while the clamping means is tightened and loosened in the assembly and separation of the housing parts.

3. A lead connector for electrical apparatus as defined in claim 1, and wherein said clamping means comprises levers at opposite sides of the base wall of one of the housing parts and extending laterally of the latter mentioned base wall in spaced relationship to the end wall of said one of the housing parts, said levers having fulcrum surfaces aligned with the insulating blocks and terminal elements, an adjustable clamping member connecting the levers at one side of the fulcrum surfaces, and fixed holding elements on the other housing part for engagement with the levers at the sides of the fulcrum surfaces opposite the adjustable clamping member.

4. A lead connector for electrical apparatus as defined in claim 3, and further characterized by engageable latch elements on the levers and the fixed holding elements for releasably holding the housing parts together while the adjustable clamping elements are tightened or loosened.

5. A lead connector for electrical apparatus comprising two housing parts which fit together to provide a hollow box-type enclosure, said housing parts each having base and end walls adjoined together at adjacent ends and extending in angular relationship to one another from the adjoined ends, each housing part being open opposite said base and end walls, said base and end walls of each part also having end portions opposite the adjoined ends which interfit respectively with end por-

tions of the end and base walls of the other part in the assembly of the parts, said base walls and said end walls of the two parts respectively being in spaced and directly opposed relationship to one another when the parts are assembled, the end walls of the parts each having an opening therein for the passage of lead wires therethrough, terminal elements mounted in spaced relationship to one another in each of the housing parts in the angle formed between the base and end walls, said terminal elements each having a substantially flat contacting face thereon, said contacting faces of the terminal elements being spaced from one another and disposed in substantially normal relationship to the base and end walls of the part in which they are mounted, insulating blocks mounted adjacent the terminal elements on the sides thereof opposite the contacting faces, said terminal elements and insulating blocks being grouped in staggered relationship in the two housing parts to provide a series of contacting terminal elements and insulating blocks with the contacting faces of the terminal elements engaged when the housing parts are assembled in aligned relationship to one another longitudinally of said series, and clamping means secured to one of the housing parts and engageable with portions of the other housing part for holding the parts together when the housing parts and terminal elements are fitted together.

6. A lead connector as defined in claim 5, and wherein said clamping means includes adjustable parts for applying pressure through said series of contacting terminal elements and insulating blocks.

7. A lead connector for electrical apparatus comprising two housing parts which fit together to provide a hollow box-type enclosure, said housing parts each having two walls adjoined together at adjacent ends and extending in angular relationship to one another from the adjoined ends to provide substantially L-shaped structures of corresponding sizes which fit together in inverted and opposed relationship to one another to define a substantially rectangular interior space therebetween, one of said walls of each of the parts having an opening therein for the passage of lead wires therethrough, terminal elements mounted in spaced and substantially parallel relationship to one another in each of the housing parts in the angle formed between the said two walls thereof, said terminal elements each having substantially parallel flat faces on opposite sides thereof disposed in substantially normal relationship to said two walls of the part in which they are mounted, insulating blocks interposed between the flat faces of alternate pairs of adjacent terminal elements in the housing parts and at the outer flat faces of the terminal elements in one housing part, said terminal elements and insulating blocks being in staggered relationship relative to one another in the two housing parts to provide a series of contacting terminal elements and insulating blocks when the housing parts are assembled with the L-shaped structures in laterally aligned relationship to one another, and releasable latch means on the housing parts for holding the parts together.

8. A lead connector for electrical apparatus as defined in claim 7, and wherein said releasable latch means includes adjustable clamping structure for applying pressure through said series of contacting terminal elements and insulating blocks while the latch means is engaged.

9. In a lead connector for electrical apparatus, the combination comprising two separable parts, each of said parts including terminal elements having contacting surfaces thereon and located entirely within the outer surface limits of the parts, the contacting surfaces on the terminal elements of each of the two parts being in substantially parallel relationship to one another and aligned for engagement with the contacting surfaces of the terminal elements of the other part when the parts are aligned and engaged with one another, insulating spacers engaged with the terminal elements on the sides

thereof opposite the contacting surfaces of each part which establishes a series of engaging terminal elements and insulating spacers extending laterally of the contacting surfaces when the parts are engaged, means exterior to opposite sides of the parts for gripping and applying pressure to said series of terminal elements and insulating spacers for holding the contacting surfaces of the engaged parts in firm contact with one another, and clip elements for holding the insulating spacers and terminal elements of each part in aligned relationship when the 10 pressure of the gripping means is relieved.
